(57) **CLAIM**

The ornamental design for a bottle with opposed sealable openings, as shown and described.

DESCRIPTION

FIG. 1 is a top, front, and left side perspective view of a bottle with opposed sealable openings showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a right side elevational view with the hinged portion of the top and bottom caps shown in opened condition.

The broken lines shown in the drawings are included for the purpose of showing environmental structure that forms no part of the claimed design.
